HOOK FOR SHOWER CURTAINS OR THE LIKE

Ned Strongin, Baldwin, N.Y., assignor to Heinz
Nathanson Incorporated, New York, N.Y.

Filed Nov. 19, 1971, Ser. No. 200,660

Term of patent 14 years

Int. Cl. D8—08

U.S. Cl. D8—248

FIG. 1 is a perspective view of the hook for shower curtains or the like according to my invention;

FIG. 2 is a front elevation of the hook shown in FIG. 1;

FIG. 3 is a rear elevational view of the hook shown in FIG. 1;

FIG. 4 is a top view of the hook shown in FIG. 1;

FIG. 5 is a side elevational view of the hook shown in FIG. 2 taken from the left of FIG. 2; and

FIG. 6 is a side elevational view of the hook shown in FIG. 2, taken from the right of FIG. 2.

I claim:

The ornamental design for a hook for shower curtains or the like, substantially as shown.
